UNITED STATES PATENT OFFICE.

REISSUED

ROBERT FARIES, OF DECATUR, ILLINOIS, ASSIGNOR TO WALRUS MANUFACTURING COMPANY, OF DECATUR, ILLINOIS, A CORPORATION OF ILLINOIS.

JAR AND DIPPER FOR SERVING CRUSHED FRUIT OR THE LIKE.

SPECIFICATION forming part of Letters Patent No. 779,271, dated January 3, 1905.

Application filed April 18, 1904. Serial No. 203,742.

To all whom it may concern:

Be it known that I, ROBERT FARIES, of the city of Decatur, county of Macon, and State of Illinois, have invented a certain new and 5 useful Jar and Dipper for Serving Crushed Fruit or the Like, of which the following is a specification.

This invention is intended for use in beverage - dispensing outfits, commonly called 10 "soda-fountains." It is exemplified in the structure hereinafter described, and it is defined in the appended claims.

One object of the invention is to provide a jar and dipper so shaped and proportioned that 15 the dipping edge of the dipper may be presented downward to receive a filling of the contents of the jar and the dipper may be raised in an approximately horizontal position by placing the back of the dipper-rod against 20 a side of the mouth of the jar.

Another object is to so arrange the cover with relation to the dipper that when the dipper is level inside the jar the cover will be to 25 one side out of the range of view to the operation of lifting and tipping the dipper.

Another object is to have the handle by 30 which the cover and the dipper are raised always outside the jar, so as not to be contaminated by the contents of the jar.

Another object is to so shape or mark the handle or the cover as to indicate the position 35 of the dipping edge of the dipper from outside the jar.

Another object is to have the handle so 40 formed and placed in relation to the dipper that when the handle is grasped in the natural way and in conformity to the markings that indicate the front edge of the dipper the dipper will be in proper position for raising and 45 tipping.

Another object is to shape the jar and the dipper that practically all the contents of the jar may be readily removed by the dipper.

In the drawings forming part of this specification, Figure 1 is an elevation of an embodiment of my invention, showing the cover in

place on the jar. Fig. 1^a is a plan of the cover and a handle thereon. Fig. 2 is an elevation showing the cover moved to one side of the mouth of the jar and the dipper partly raised 50 out of the jar. Fig. 3 is a plan of the label-plate. Fig. 4 is a section through the label-plate on line X in Fig. 3. Fig. 5 shows the jar sustained in a receptacle containing cold water and illustrates a desirable use of the 55 principal features of the invention.

The jar 1 is preferably made of glass with a hemispherical bottom 4, and it has an annular groove 2 near its upper end surmounted by an annular ledge 3. The cover 5 is adapted to close the mouth of the jar. A rod 6 extends downward from the under surface of the cover, and a dipper 7 is attached at one side to the lower end of rod 6. The cover and the dipper are so connected that when 65 the cover is in place on the jar in an approximately horizontal position the dipper will occupy a space near one side of the lower end of the jar, with its dipping edge inclined downward and away from such side. The cover has a 70 handle 8, shaped to aid in lifting the cover with the dipper in a dipping position, and in this instance the handle is also formed to indicate the dipping edge of the dipper. The handle preferably consists of a ring which is rigidly secured 75 to the cover, which is curved flatwise, with its upper part inclined in the direction in which the dipper extends from rod 6 and which is practically a continuation of the dipper-rod. The different parts of the dipping appliance and 80 cover are secured together rigidly, and whenever the handle is grasped in a certain way, indicated by the bend of the handle or by other forms or markings, the dipper is sure to be in proper position for raising and tipping.

When the jar is used on a counter, it is provided with a sustaining-frame composed of a set of vertical rods 9, which terminate in legs 90 extending below the bottom of the jar, and rings 11 and 12, secured to rods 9 and encircling the jar. Ring 11 is cut or separated at

11^a, and it is sprung into groove 2 under ledge 3. The legs of the supporting-frame are preferably provided with rubber balls 10 on their feet, so as not to scratch or mar the counter-
5 top.

The label-plate 13 has a lug 14, which is bent to conform to groove 2 of the jar and to the ring encircling such groove, and it is held in place removably by inserting the lug be-
10 tween the ring and the jar. In this instance the ring that holds the label-plate in place is a part of the supporting-frame; but it is ob-
15 vious that the function of holding the label is independent of the function of supporting
15 the jar and that the ring holding the label need not be a part of the supporting-stand.

When used in direct connection with a soda-
fountain, the jar may be supported in a recep-
20 tacle, as 15, containing cold water from the
ice of the soda-fountain, and in that case a
gasket 16 may be used to take the weight of
the jar through ledge 3 and form an air-tight
joint.

The concave bottom of the jar makes it pos-
25 sible for the dipper to get about all the con-
tents of the jar without special manipulation,
and when the cover is moved to the side of
the jar opposite the dipping edge of the dipper
30 the obliquity of rod 6 will permit the dipper
to assume an approximately level position
beneath the exposed part of the mouth of the
jar, as shown in Fig. 2.

While the jar is particularly applicable to
the dispensing of crushed fruits and syrups,
35 its utility is not necessarily confined to that
purpose, and it may be used to serve any be-
verage or refreshment desired.

When the cover and dipper are manipulated
by the dispenser alone, a flattened handle is
40 a sufficient guide for him to locate the posi-
tion of the dipping edge after having once
used the dipper and replaced it; but when the
jar is placed on the counter, as will usually
45 be the case when the jar is used as a substi-
tute for the crushed-fruit bowl, it will be ac-
cessible to the public, and meddlesome per-
sons will be likely to move the cover from the
position in which the dispenser left it. Under
50 these circumstances some distinguishing mark
will become necessary to locate the position of
the dipping edge of the dipper, and the curved
ring which constitutes the handle will meet
that demand more or less completely. If de-
sired, however, an additional mark or indicat-
55 ing characteristic may be placed on the cover
above the dipping edge of the dipper, as shown
at 15^a in Figs. 1, 1^a, and 2, and this mark may
also aid the dispenser in determining the con-
tents of the jar. In this case the label bears
60 the word "Pineapple" and the auxiliary mark
to indicate the location of the dipping edge of
the dipper is a "P," and the initial of the

name on the label may be similarly used in
other cases.

The mouth of the jar is wide, the jar is wide 65
in proportion to its length, the rod of the dip-
per inclines backward from the cover of the
jar, and the dipping edge of the dipper in-
clines downward from the rod at an incline
70 somewhat in excess of a right angle, all ap-
proximately as shown in the drawings, so that
the contents of the jar may be readily dipped
up and raised out of the jar without losing any
material part of a dipperful.

By making the bottom of the jar concave 75
and shaping the ladle to conform in a general
way to the concave surface the entire contents
of the jar may be readily removed.

I claim—

1. The combination of a jar having a round-
80 ed bottom, a cover for the jar, a rod extend-
ing downward from the under side of the cover
and a ladle on the lower end of the rod shaped
to conform in a general way to the concavity
85 of the bottom of the jar.

2. The combination of a jar, a cover for the
jar, a dipper adapted to enter the jar, a con-
nection between the cover and the dipper hold-
ing the dipping edge of the dipper always pre-
90 sented in a certain direction with relation to
the cover and a mark or configuration on the
upper surface of the cover to indicate the di-
rection in which the dipping edge of the dip-
per is presented.

3. The combination of a jar, a cover for the
95 jar, a rod extending below the cover, a dipper
on the lower end of the rod with its dipping
edge extended away therefrom and a handle
above the cover rigidly connected with the rod
and shaped to aid in lifting the dipper in a 100
proper filling and emptying position.

4. The combination of a jar having a wide
mouth, a cover for the mouth of the jar, a rod
attached to the cover and extended downward
therefrom and a dipper on the lower end of 105
the rod inclined to the rod at such an angle that
when the rod is against a side of the mouth
of the jar the dipper may be made to assume
an approximately horizontal position.

5. The combination of a jar having a wide 110
mouth, a cover for the mouth of the jar, a rod
attached to the cover and extended obliquely
downward therefrom and a dipper on the lower
end of the rod inclined to the rod at such an
angle that the dipper may be made to assume 115
an approximately horizontal position inside
the jar.

In testimony whereof I sign my name in the
presence of two subscribing witnesses.

ROBERT FARIES.
